ADJUSTABLE LENGTH COAXIAL
TRANSMISSION LINEJames L. Clark, Cambridge, Mass., assignor to
the United States of America as represented by
the Secretary of War

Application November 27, 1945, Serial No. 631,182

3 Claims. (Cl. 178—44)

1

This invention relates generally to electrical apparatus and more particularly to coaxial transmission lines.

Often it is desirable to tune a coaxial transmission line by means of an associated coaxial transmission line having an adjustable shorting plunger. Such a tuning stub having a movable shorting plunger is usually arranged to permit the excursion of the shorting plunger to extend substantially the entire length of the coaxial transmission line tuning stub.

Such a required excursion of the shorting plunger is often mechanically undesirable.

The required excursion of such a shorting plunger can be substantially reduced by having the coaxial transmission line tuning stub adjustable in length.

It is an object of the present invention to provide an adjustable length coaxial line.

More specifically it is an object of the present invention to provide a means for changing the effective length of a coaxial transmission line whose overall dimension is determined by stacking several lines together and connecting the desired lengths by the use of a switching end plug.

Several coaxial lines of different lengths are stacked together and at one end all lines terminate in a common plane which is at right angles to the longitudinal axes of the lines. At that end of the coaxial transmission lines there is provided a switching plug having terminals which connect together two or more lines, the total length of these connected lines being equal to the desired total length of line.

Other objects, features and advantages of this invention will suggest themselves to those skilled in the art and will become apparent from the following description of the invention taken in connection with the accompanying drawings in which:

Fig. 1 is an elevation of a device embodying the principles of this invention;

Fig. 2 is a side view of Fig. 1;

Fig. 3 is an elevation of a switching plug associated with the device shown in Figs. 1 and 2;

Fig. 4 is a side view of Fig. 3;

Fig. 5 is a schematic representation of the electrical circuit obtained by the use of the devices shown in Figs. 1, 2, 3, and 4; and

Fig. 6 is a schematic representation of an alternate electrical circuit obtained by the use of the devices shown in Figs. 1, 2, 3, and 4.

Referring now to Figs. 1 and 2, a framework 10 has four holes bored to receive and hold four coaxial transmission lines 11, 12, 13 and 14. Co-

axial transmission lines 11, 12, 13 and 14 are each formed from a single length of line 22, terminate in framework 10, and that coaxial transmission line 14 has a movable shorting plunger 15. Coaxial transmission line 13 is characterized by an inductive coupling loop 16 which is formed from the inner conductor of that line where that inner conductor breaks the confinement of its associated outer conductor.

It should be noted that the portions 11 and 12 are formed from a single length of line 22, terminate in framework 10, and that coaxial transmission line 14 has a movable shorting plunger 15. Coaxial transmission line 13 is characterized by an inductive coupling loop 16 which is formed from the inner conductor of that line where that inner conductor breaks the confinement of its associated outer conductor.

Referring now to Figs. 3 and 4, a switching plug 17 has four terminals 18, 19, 20 and 21, respectively, with terminals 18 and 19 electrically connected and terminals 20 and 21 electrically connected. Terminals 18, 19, 20 and 21 are disposed at 90 degree intervals about the circumference of a circle whose center coincides with the center of a face of switching plug 17.

In Figs. 1 and 2 coaxial transmission lines 22, 13, and 14 are similarly disposed in framework 10 and the hollow inner conductors receive and make contact with the terminals of switching plug 17 of Figs. 3 and 4.

Fig. 5 shows the resulting circuit when switching plug 17 is inserted in framework 10 such that terminals 20 and 21 connect together the inner conductors of coaxial transmission lines 13 and 14.

Fig. 6 shows the resulting circuit when switching plug 17 is rotated 90 degrees from the position assumed in the above paragraph. Under these conditions, terminals 18 and 19 of switching plug 17 connect together the inner conductors of coaxial transmission lines 22 and 13 and terminals 20 and 21 of switching plug 17 connect together the inner conductors of coaxial transmission lines 22 and 14.

The apparatus shown in the drawings which embodies the principles of the invention herein disclosed is a means for extracting radio frequency energy from an open line type oscillator tank circuit and the presentation of that energy to an antenna or other load. For example, radio frequency energy may be coupled from a given source by means of coupling loop 16 of line 13 and transmitted to any load (not shown) connected to one end of line 13. Lines 22 and 14 are connected to the other end of line 13 by means of a switching plug 17, resulting in the circuit shown in Fig. 6. An alternate interconnection made possible by rotating switching plug 17 90 degrees, results in the circuit shown in Fig. 5 in which line 14 only is connected to line 13.

Under the latter conditions, line 22 forms no part of the operating circuit.

Depending upon the frequency of operation, either of the two above connections may be made by switching plug 17 and line 13 can be tuned by adjusting shorting plunger 15 in line 14.

The ability to remove or add line 22 to the operating circuit by the simple method of removing switching plug 17, rotating it 90 degrees, and then reinserting it, provides a means for effectively changing the length of the tuning line associated with line 13. Accordingly, the required excursions of shorting plunger 15 in line 14 to accomplish tuning are substantially reduced even though the operating frequency range of the device is quite large.

It will be apparent that there may be deviations from the invention as described which still fall fairly within the spirit and scope of the invention.

Accordingly I claim all such deviations which fall fairly within the spirit and scope of the invention as identified in the hereinafter appended claims.

What is claimed is:

1. An adjustable length coaxial line comprising a first coaxial transmission line having an inner conductor and an outer conductor, means at one end for connecting said line to a load, means at an intermediate position along said line for connecting said line to a generator, a second coaxial transmission line having an inner conductor and an outer conductor, a movable shorting plunger in said second line, a third coaxial transmission line having an inner conductor and an outer conductor bent in a generally U shape, said lines being stacked together with the end of said lines terminating in a common plane at right angles to the longitudinal axes of said lines, and means including a switching plug having four terminals with pairs of said terminals electrically connected for making the desired interconnections between the inner conductors of said lines, whereby the

effective length of said first coaxial transmission line is altered.

2. An adjustable length coaxial line comprising a first coaxial transmission line having an inner conductor and an outer conductor, means at one end for connecting said line to a load, means at an intermediate position along said line for connecting said line to a generator, a second coaxial transmission line having an inner conductor and an outer conductor, a movable shorting plunger in said second line, a third coaxial transmission line having an inner conductor and an outer conductor bent in a generally U shape, and means including a switching plug having four terminals with pairs of said terminals electrically connected for making the desired interconnections between the inner conductors of said lines, whereby the effective length of said first coaxial transmission line is altered.

3. An adjustable length coaxial line comprising a plurality of coaxial transmission lines, each of said lines having an inner conductor, said lines being stacked in such a manner that an end of each of said lines terminates in a common plane, and means including a switching plug having a plurality of terminals, said terminals electrically connected in pairs for interconnecting the inner conductors of said lines, whereby the effective length of said coaxial transmission lines is altered.
